UNITED STATES PATENT OFFICE.

WM. LOUGHridge, OF WEVERTON, MARYLAND.

ARRANGEMENT OF MEANS FOR FREEING CANAL-BOATS FROM WATER.

Specification of Letters Patent No. 11,293, dated July 11, 1854.

To all whom it may concern:

Be it known that I, WILLIAM LOUGHridge, of Weverton, in the county of Frederick and State of Maryland, have invented 5 a new and useful Improvement in the Mode of Freeing Canal-Boats and other Vessels from Water; and I do hereby declare that the following is a full, clear, and exact description of the construction and operation 10 of the same, reference being had to the annexed drawing, forming part of this specification, in which—

Figure 1 is a plan of interior of boat, showing the arrangement for effecting the 15 removal of the water. Fig. 2 is a vertical section on line $\alpha\alpha$ of Fig. 1. Fig. 3 is a view showing the operation of my arrangement. Fig. 4 is a front view of roller and tube.

20 Similar letters refer to the same part.

My invention has for its object the discharge of the leakage from canal boats and other vessels without the employment of pumps.

25 It consists in the peculiar arrangement of a float in the interior of the vessel, combined with a tube operating on the siphon principle, by which the discharge is rendered automatic and the vessel freed from its leakage at all times, without the assistance of the crew, rendering examinations as to the 30 quantity of water made unnecessary and obviating the necessity for a watch to pump out during the night.

35 The construction and arrangement of my improvement, as well as its operation, will be understood by the following description, reference being made to the drawing, in which—

40 A represents the boat, and the space between a and a' the thickness of the bottom planking, in which I insert a bent tube b open at one end (c), and connected at the other with a metal or gutta percha tube d .

45 The open mouth c is slightly above the surface of the plank, and has resting upon it a valve e , having on its under surface an elastic pad for giving a perfect contact with the mouth c of the tube. This valve is se- 50 curely fastened to a float B , kept in position by means of arms $f f'$ perforations in which pass over standards h . This float is placed between the ribs and bottom and floor of the boat, and will rise so as to free the mouth c of the tube b on the admission of a very 55 slight depth of water to the hold of the

boat by leakage. The gutta percha tube d after ascending to the deck is wound around a reel m , as shown in Fig. 4, so as to be conveyed to any position without the boat and 60 within the limits of the tube.

The operation of the interior arrangement pertaining to my invention will be shown by Fig. 2, where for illustration the tube is bent around the outer surface of the vessel A and permitted to terminate at a lower level than the bottom of the boat. Now if there be a leak in the bottom of the boat A , when a proper depth of water has covered the bottom, the float B will rise, and lift 70 the valve e from the mouth c of the tube b . Then if the air be exhausted from the tube d the water will flow from the mouth of the tube d , and the valve continue to fall until the water in the hold is nearly down to the 75 level of the mouth c of the tube b , when the attraction of the mouth of the tube overcomes the buoyancy of the valve end of the float B , the valve e drops upon the mouth c of the tube before said mouth has become 80 uncovered for the admission of air. A rise of the water in the hold sufficient to overcome the attraction of the mouth c of the tube for the valve e , lifts the float and opens the mouth c of the tube b , causing the discharge of the water from the lower end of the tube d to be resumed, which discharge will continue until the valve e again drops on the mouth c , as before. In this way when 85 my mode of discharge is once put in operation a rise of water in the hold sufficient to lift the float will produce an immediate discharge from the mouth of the tube d , which will continue until the depth of water is so reduced that the valve e drops upon the 90 mouth c of the tube b and stops the flow, thus rendering the operation of this water deliverer automatic, and always preventing a rise of water in the hold above that required to cover the mouth c of the bent 95 tube b .

In practice the interior arrangement will be similar to that shown in Figs. 1 and 2, but the tube d , which will be made of gutta percha, will after passing above the deck be wound on a reel m , as shown in Fig. 4, so as to be run on shore as will be hereafter described. When the boat is tied up for the night the reel is rolled off the deck, permitting the tube to unwind, as shown in Fig. 3. 100 The reel is run down the berm bank, or any suitable situation given the tube d which

will bring the end *q* lower than the bottom of the boat. Air is then expelled from the tube by a small air pump, or by pouring water into the end *q* of the tube, or in any 5 suitable manner. The discharge will then begin and continue, as above described, until the valve *e* shuts down on the end *c* of the tube *b*. When the water rises in the hold to lift the float the discharge is resumed, and 10 will continue until stopped by the dropping of the valve *e*, the operation in practice being as explained from Figs. 1 and 2, the tube *d* discharging the leakage whenever the water rises above the floating point of the 15 float *B*, without the necessity of any watch or the interposition of any human agency.

The water discharging arrangement is of the greatest importance on canals where cargoes are often greatly damaged by negligence on the part of the watch in pumping 20 out the leakage, though it may be rendered

available for many other purposes which require a similar discharging arrangement.

I do not of itself claim the discharge of water from the vessel by the exhausted tube 25 *d*; but

What I do claim as new and of my own invention is—

The herein described arrangement of float, 30 valve, and bent tube in the bottom of the boat, by which the discharge of water is rendered automatic, and the boat freed from leakage, substantially as herein before set forth.

In testimony whereof, I have hereunto 35 signed my name before two subscribing witnesses.

WM. LOUGHridge.
